UNITED STATES PATENT OFFICE

96,625

DESIGN FOR A FAUCET

Jack Robinovitz, Chicago, Ill., assignor to Filtro Faucet Manufacturing Co., Chicago, Ill., a corporation of Illinois

Application May 27, 1935, Serial No. 57,031

Term of patent 7 years

To all whom it may concern:

Be it known that I, Jack Robinovitz, residing at Chicago, in the county of Cook and State of Illinois, a citizen of the United States, have invented a new, original, and ornamental Design for a Faucet, of which the following is a specification, reference being had to the accompanying drawing, forming a part thereof.

Fig. 1 is a view in front elevation of a faucet showing my new design.

Fig. 2 is a view in side elevation thereof.

I claim:

The ornamental design for a faucet substantially as shown.

JACK ROBINOVITZ.
